UNITED STATES PATENT OFFICE.

LEWIS F. DAVOLL, OF CEDAR BLUFF, VIRGINIA

METALLIC RAILROAD-TIE.

Specification of Letters Patent. Patented Dec. 29, 1914.

1,123,111.

Application filed May 7, 1914. Serial No. 837,020.

To all whom it may concern:

Be it known that I, LEWIS F. DAVOLL, a citizen of the United States, and a resident of Cedar Bluff, in the county of Tazewell and State of Virginia, have invented a new and useful Improvement in Metallic Railroad-Ties, of which the following is a specification.

This invention relates to railroad ties, and more particularly to metallic ties.

One of the principal objects of the invention is to provide an improved metallic tie including means for removably securing the track rails in place.

Another object of the invention is to provide a tie of the class described, including means whereby the rails may be secured thereon, said means affording a rail seat having a certain amount of resiliency and affording accommodation for the contraction and expansion of the rails due to changes in the temperature.

A further object of the invention is to provide an improved metallic tie which will be extremely simple in construction, durable, efficient in operation and inexpensive to manufacture.

With these and other objects in view which will become apparent as the description proceeds, the invention resides in the construction, combination and arrangement of parts hereinafter more fully described and claimed, and illustrated in the accompanying drawing in which like characters of reference indicate like parts throughout the several figures, of which—

Figure 1 represents a top plan view of a tie constructed according to my invention, a rail being shown as secured to one end thereof, Fig. 2 represents a vertical, sectional view longitudinally of the tie and transversely of the rail taken on the plane indicated by the line 2—2 of Fig. 1, looking in the direction indicated by the arrows, and Fig. 3 represents a view of the tie, a rail being shown in place thereon, the view being taken from one end of the tie.

Referring more particularly to the drawing, the tie may be made of pressed steel, and is substantially U-shaped, and comprises a flat bottom 5, side walls 6 which diverge slightly upwardly from the bottom and are provided on their upper edges with outwardly extending horizontal flanges 7. The bottom of the tie is provided at spaced intervals with pairs of transversely disposed

depending anchoring ribs 4, punched or stamped from the metal.

A tie plate is detachably secured to each end of the tie, and comprises a body portion 8 disposed transversely of the tie, and is at its ends provided with downwardly extending engaging flanges 9, which engage over the outer edges of the flanges 7 as clearly shown in Fig. 3, the central part 65 of the body portion having its sides bent downwardly to provide substantially resilient spacing flanges 10, said flanges being of a length equal to the distance apart of side walls 6 of the tie, and being disposed 70 transversely of the tie, and snugly fitting at their ends against the side walls, said flanges diverging slightly downwardly. The spacing flanges serve to maintain the side walls 6 of the tie in uniformly spaced 75 position, and also serve to brace the side walls. The bottom edges of flanges 10 are spaced from the bottom 5 of the tie so that said bottom is clear from obstructions whereby rain water or water caused by the 80 melting of snow, may readily run off of the tie, so as to prevent unnecessary rusting of the latter.

The tie plate is flat on its upper surface, and upon it rail 11 is adapted to rest and 85 said rail is primarily secured by means of oppositely disposed retaining hooks 12, whose hooked portions 13 engage opposite edges of the base flange of the rail, and extend through openings 14 cut in the body 90 portion 8 of the tie plate, the straight or shank portions 15 of the retaining hooks extending beneath the tie plate and in substantially parallel relation with the body portion thereof, and at their outer ends extend through openings provided in the 95 spacing flanges 10 and are secured by means of nuts 16 turned upon the outer threaded ends of the shanks against the spacing flanges, for securing the rail in place. As 100 shown clearly in Fig. 1, the retaining hooks are disposed so that they engage opposite edges of the rail base and extend through opposite spacing flanges so that the rail is securely held against lateral displacement. 105 Since the spacing flanges are somewhat resilient, it is evident that any variations in the width of the rail base will be compensated for by a giving of the flanges so that the retaining hooks will always be in tight 110 engagement with the rail base and spacing flanges, yet a certain resiliency will be al-

- lowed so that the strain upon the rail incident to the passing of rolling stock there-over, will be transmitted to a certain extent to the tie plate, thus lengthening the life of the rail, and at the same time not detracting from the life of the tie plate and tie. The plate may be provided with sets of keepers for further aiding the maintenance of the rail on the plate, said keepers being arranged in pairs at each end of the plate, above the flanges 7 of the tie, said keepers comprising flat shanks 18 disposed upon the upper surface of the plate and offset upwardly at their inner ends as at 19 to provide rail base engaging portions which engage the base of the rail upon opposite sides. The shank portions 18 of the keepers are substantially of an inverted U-shape as indicated in Fig. 3, and said keepers are provided with elongated slots 20 through which extend bolts 21, which bolts also extend through openings in flanges 7 of the tie, and through openings in portions of the tie plate disposed over said flanges, whereby the tie, tie plate and keepers are secured by the same bolts, as will be readily understood. The elongated slots 20 are provided so that rails with varying widths of base flanges may be accommodated and the openings 14 through which the hook portions 13 of the retaining hooks 12 extend, are also slightly elongated for the same reason. It will be noted that the flanges 7 of the tie are provided with different sets of openings spaced apart as illustrated at 22 in Fig. 1, so that the tie plate may be shifted when found necessary longitudinally of the tie to allow for the desired location of the plate on curves or at switches. By reason of the ties and tie plates having their sides slightly divergent, a further advantage is obtained in that in shipping the parts they may be nested together, thus occupying a minimum storage and shipping space.
- Although I have described the preferred embodiment of my invention, I may desire to make such changes in the construction, combination and arrangement of parts as do not depart from the spirit of the invention and the scope of the appended claims.
- I claim:
1. A metallic cross tie substantially U-shaped, and including a flat bottom having anchoring ribs punched downwardly therefrom, side walls diverging slightly upwardly from the bottom and provided with oppositely extending overhanging flanges, tie plates disposed transversely of said tie near its ends, said plates including flat body portions spanning said ties, and resting at their ends on the said flanges, the ends of said body portions provided with engaging flanges which engage the flanges of the tie, said body portions having their central parts bent downwardly on opposite sides to provide spacing flanges which snugly fit between the side walls of the tie, for bracing the latter, said spacing flanges diverging slightly downwardly, said tie plates adapted to serve as seats for the track rails, retaining hooks for keeping said rails in place, said hooks including straight shank portions, disposed below the body portions of the plates and extending in opposite directions and projecting at their ends through openings in the spacing flanges and provided with nuts for retaining the hooks, said hooks having hooked portions extending upwardly through openings in the body portion of the plates and engaging the opposite edges of the base flanges of the rails, and keepers disposed oppositely in pairs upon said plate, and above the tie flanges, said keepers including shank portions of substantially U-shape, said shank portions at their inner ends offset to provide base flange engaging portions, and securing means extending through the tie flange, tie plates and keepers for securely binding the parts together.
  2. A metallic tie of substantially U-shape, comprising a bottom, spaced side walls, flanges formed on said side walls, tie plates disposed transversely of said ties and provided with flanges engaging the tie flanges and further provided with spacing flanges disposed between the walls of the tie, hooks carried by said tie plates for securing the track rails in place, said hooks being oppositely disposed and including shank portions extending at their ends through opposite spacing flanges and further including hook portions extending through the tie plate, keepers disposed on said plate for further securing the track rails, and connecting means between said keepers, tie plates and tie flanges, for securing the parts together.
  3. A tie of substantially U-shape, including side walls, a bottom and flanges, tie plates disposed on said ties and provided with flanges engaging the tie flanges, spacing flanges provided on said tie plates and disposed between the walls of the tie, retaining hooks carried by said tie plates for securing the track rails in place, and keepers carried by said tie plates for further securing the said rails.
  4. A railroad tie comprising spaced side walls, tie flanges, and a tie plate disposed on said tie, means provided on said plate for engaging the tie flanges, means on said plate for maintaining said side walls in spaced relation and for bracing them, means carried by the tie plate for securing a track rail in place, and keepers carried by the plate for securing the track rail.
  5. A railroad tie including side walls, tie plates secured to the side walls, means carried by the plates for securing track rails

in place, and resilient spacers between the side walls and connected with the securing means for resiliently maintaining the latter.

5. 6. A railroad tie including side wall, and flanges, a tie plate disposed on said tie and provided with means for engaging the tie flanges, spacing flanges formed on the tie plate and disposed between the side walls, 10 said spacing flanges diverging at their lower ends and rail securing means carried by said tie plate, said means including shanks oppositely disposed and extending at their ends through said spacing flanges and provided with nuts, said shanks provided at 15 their opposite ends with hooks extending through openings in the tie plate and adapted to engage the base flange of a rail.
7. In a railroad tie having spaced walls, 20 a tie plate, means for securing the same to a tie, rail engaging means carried by the tie

plate and means for resiliently anchoring the rail engaging means, said means being disposed between and adapted to space the tie walls.

- 25 8. A railroad tie providing a tie plate having depending and diverging flanges, rail retaining means carried by said plate, said means comprising shanks provided with hooks, said hooks extending through 30 openings in the plate and adapted to engage the opposite edges of the base flange of a rail, the shanks being disposed in opposite directions to each other and extending through the diverging flanges and provided 35 with retaining means, whereby a resilient seat is provided for said rail.
